US0D1036433S

(12) **United States Design Patent** (10) **Patent No.:** **US D1,036,433 S**
(45) **Date of Patent:** **** Jul. 23, 2024**

(54) **DISPLAY DEVICE**

(71) Applicant: **Samsung Display Co., Ltd.**, Yongin-si (KR)

(72) Inventors: **Yun Joo Yim**, Seoul (KR); **Seon Hee Kim**, Seoul (KR)

(73) Assignee: **Samsung Display Co., Ltd.**, Yongin-si (KR)

(**) Term: **15 Years**

(21) Appl. No.: **29/791,308**

(22) Filed: **Jan. 7, 2022**

(30) **Foreign Application Priority Data**

Jul. 9, 2021 (KR) 30-2021-0032758

(57) **CLAIM**

The ornamental design for display device, as shown and described.

DESCRIPTION

FIG. 1 is a perspective view of the display device according to the present design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is a perspective view of the display device, shown in an alternate configuration;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines indicate unclaimed portions of the article that form no part of the claimed design.

1 Claim, 14 Drawing Sheets
